2 Sheets-Sheet 2

UNITED STATES PATENT OFFICE

EARL E. PRICE, OF MINNEAPOLIS, MINNESOTA

SILO CLOSURE

Application filed October 6, 1928. Serial No. 310,894.

My invention relates to silo closures and has for an object to provide a closure employing a U-shaped lever for latching the door in place, which lever normally extends outwardly from said frame in such a manner as to serve as a step, which lever further may be completely detached from said frame to permit of removing the door bodily from the frame, and further serves as a handle in handling the door, and particularly such closures as employ a frame of U-shaped cross section adapted to fit in the wall of the silo closed through a door held in firm contact with the edges of said frame.

Another object of the invention resides in forming a lug on said step and in providing a cam member on said frame adapted to co-operate with said lug for causing the door to be drawn closed upon the swinging of said lever into its extended position.

A still further object of the invention resides in providing ears on said door and in pivotally attaching said lever to said ears by means of bolts extending therethrough.

A still further object of the invention resides in employing in conjunction with the closure means for moving said lug and cam relative to one another, said means serving to adjust said lug and cam member relative to one another so as to vary the pressure of the door upon the frame.

A feature of the invention resides in constructing said cam member of Z-shaped cross-section and of attaching the same through one of the legs thereof to the frame member, the other of the legs of said cam member being offset relative to said frame to permit of movement of said lug without engagement with said frame and to distribute the wear upon said cam member over the entire surface thereof.

A feature of the invention resides in providing said closure with auxiliary steps extending through the outer flange of said frame and being attached to the webs thereof, said auxiliary steps extending in inclined relation to the step attached to said door and forming in conjunction therewith a ladder.

With the foregoing and other objects in

view, which will appear in the following description, the invention resides in the novel combination and arrangement of parts and in the details of construction hereinafter described and claimed.

In the drawings:

Fig. 1 is an elevational view of a silo closure embodying one form of my invention.

Fig. 2 is a plan sectional view taken on line 2—2 of Fig. 1.

Fig. 3 is a vertical sectional view taken on line 3—3 of Fig. 1 and drawn to an enlarged scale.

Fig. 4 is a view similar to Fig. 2, illustrating another form of the invention.

Fig. 5 is a vertical sectional view taken on line 5—5 of Fig. 4 and drawn to an enlarged scale.

Fig. 6 is a view similar to Fig. 2 of still another form of the invention.

In the construction of silo closures considerable inconvenience has been encountered where the closure requires the use of more than one hand in applying the same. In ordinary practice the attendant usually requires one hand to hold himself in place upon the ladder and hence has but one hand free with which to handle the door and effect the closure thereof so as to seal the interior of the silo. With my invention the desired results can be readily obtained since the handle attached to the door operates upon a simple downward movement to latch the door in place and further serves as a step for use in climbing upon the exterior of the silo.

My invention proper consists of a frame A adapted to be set into the wall of the silo in which is mounted a door B for closing the opening through said frame. This door is held closed by means of a latching mechanism C which may be conveniently manipulated by hand and which serves to hold the door in proper position. When the door B is unlatched, the same may be completely removed from the frame so as to provide a clear opening therethrough for access into the interior silo and for the purpose of the removal of the contents thereof.

The frame A as best shown in Figs. 1 and 3 comprises stiles 10 and 11, a header 12 and a

threshold 13, which are preferably constructed of U-shaped cross-section formed with a web 14 and flanges 15 and 16 extending outwardly therefrom in parallel relation. The header 12 and threshold 13 are preferably formed arcuate so as to cause the same to conform to the curvature of the silo when installed in a circular silo. The frame A may be constructed of sheet metal if desired, and bent to form the flanges and properly united at the corners to form a rigid or unitary construction, or the same may be constructed of formed metal or cast or otherwise constructed. The door B is preferably constructed of sheet metal which may be formed from a single sheet of material and when constructed of sheet metal is preferably dished as indicated at 17 to provide a flange 18 extending completely around the outer periphery of the same. The dished portion 17 is of such a size as to fit within the opening of the frame A adjacent the flange 16 thereof and is preferably chamfered so as to cause the edges 19 thereof to guide the door into closing position when applied to the frame structure. When the door is closed, the flange 18 formed on door B rests snugly upon the flange 16 forming an airtight closure for the opening through the frame so as to effectively seal the interior of the silo. Due to the lightness of sheet metal pressed into the desired form the door B is preferably so constructed though it can be readily comprehended that the same may be constructed of wood, cast metal or any other desirable material so long as the same has sufficient rigidity to cause the door to clamp tightly along the edges thereof when the latching mechanism C is applied to hold the door closed. Along the inner surface of flange 18 may be attached a sheet of metal 75 which serves as a sort of jacket forming a dead air space between it and the dished portion 17 which insulates the closure and prevents injury to the contents of the silo by frost.

For the purpose of attaching the latching device C to the door proper the following construction is employed: Intermediate the upper and lower edges of the door B adjacent the stiles 10 and 11 of the frame A are cut two vertical slots 20 and 21. Two attaching members 22 and 23 are employed which are formed with bases 24 and ears 25 extending outwardly therefrom. These ears are adapted to be passed through the slots 20 and 21 and the bases 24 are securely riveted or welded to the body of the door proper by means of rivets 26. The attaching members 22 and 23 may be constructed of T iron cut so as to form the ear 25 from the web thereof, the remainder of the web being removed to form the flange into the base 24 of said attaching members. When so constructed, the same are extremely rigid and will resist the stresses normally imposed thereon. By posi-

tioning the bases 24 of said members within the dished portions 17 of the door B the outer surface of the door is practically smooth except for the ears 25 extending outwardly therefrom. Due to the fact that the bases 24 extend completely around the ears 25 a tight joint is formed at the slots 20 and 21 so as to form an airtight connection between said ears and door. The bases 24 in addition serve to distribute the pressure upon the door more uniformly along the entire length of the flange 18 so that a perfect seal is effected throughout the entire surface of contact of the door with the frame. It is to be noted that the frame is constructed of sufficient rigidity so that the same does not give upon applying pressure to the ears 25 in order that the contact of the frame and the door be uniform throughout its extent.

The type of latching device C shown in Figs. 1, 2 and 3, comprises primarily a U-shaped lever 27 which serves as a handle for handling the door when removed from the frame and which also serves as a step when the door is properly latched and said lever is disposed in its extended position. This lever may be constructed of a bar of metal bent into the desired form as shown in Fig. 2, with arms 28 and 29 and a portion 30 connecting the same. The extreme ends of the arms 28 and 29 are drilled to receive two bolts 31 and 32 which pass through slots 33 formed in the ears 25, which slots extend in an outward direction from the door proper. The burrs 34 for the said bolts bear against the ears 25 and serve to hold the lever 27 in pivotal relation upon the door proper. By means of said slots 33 the lever 27 may be moved inwardly and outwardly relative to the door B for a purpose to be presently described, the bolts 31 and 32 moving within the slots 33 which form the pivots on which the said lever swings. The extreme ends of the ears 25 are bent toward one another to provide angular portions 35 which are drilled to receive set screws 36. These set screws are so disposed as to engage the burrs 34 of the bolts 31 and 32 so as to hold the said bolts in adjusted position within the slots 33. By means of these set screws the position of the bolts 31 and 32 may be adjusted so as to give the desired adjustment to the latching device as will be presently explained.

The latching device proper consists of a cam member 37 which is preferably formed of heavy sheet metal bent into Z-shaped cross-section as shown in Fig. 1 having two flanged portions 38 and 39 connected with a web portion 40. The cam members 37 are attached to the stiles 10 and 11 of the frame A with the flanges 38 thereof in contact with the web portions 14 of said frame and securely riveted thereto by means of rivets 41. With this arrangement the flanged portions 39 are offset from the surface of the web por-

tions 14 of the stiles 10 and 11 as shown in Fig. 1. The flanged portions 39 of the two cam members 37 are cut away to form cam surfaces 42 shaped as best illustrated in Fig. 5. These cam surfaces are so designed that when the door B is closed the said surfaces conform to spirals having the centers thereof disposed at the pivots for the lever 27, the upper portions of said cam surfaces approaching the centers of the spirals. On each of the arms 28 and 29 of the lever 27 is attached a lug 43 which is adapted to cooperate with its respective cam surface and to draw the door inwardly into closing position upon 10 swinging the lever 27 from its position illustrated in dotted lines at 44 in Fig. 3 to its position in full lines. The bottom of the cam surface 42 indicated at 45 is constructed so as to form a stop for holding the lever 27 in substantially horizontally and outwardly extending position. When so disposed, the said lever forms a step on which the attendant may stand while climbing on the silo or while 20 manipulating the door on entering the silo 25 proper.

To prevent accidental injury in the event that either of the bolts 31 or 32 become loosened or the threads thereof stripped so as to detach the step 27 from the door B, each of 30 the cam members 37 is provided with a guard 46 which is formed on the flanged portion 39 of said cam member and is disposed outwardly from the cam surface 42. This guard 35 in conjunction with the stop 45 prevents the step from falling completely away from the frame A so as to prevent accident to the attendant upon stepping on an unsafe step.

In conjunction with the steps 27 I employ auxiliary steps 47 and 48 which are similar 40 to the steps 27, being provided with arms 49 and 50 and a connecting portion 51. The arms 49 and 50 are arranged to pass through slots 52 in the flanges 15 of the frame A near the upper and lower portions of the same and 45 lie close to the inner surfaces of the webs 14 of said frame where the said arms are riveted thereto through rivets 53. It will be noted that the steps 47 and 48 are angularly disposed relative to the frame A so that when the 50 closures are set in the silo the required distance apart said steps 47 and 48 of the various closures form the individual rungs of a continuous ladder.

In Figs. 4 and 5 I have shown another form 55 of the invention in which the step 27 is directly pivoted to the ears 25 through rivets or bolts 54, while the cam members are themselves adjusted relative to the frame proper. For this purpose a mounting 55 is employed 60 which is attached to each of the stiles 10 and 11 of frame A and is arranged with a wall 56 spaced from and substantially parallel to the web 14 of said stiles. These mountings 65 are constructed with angular portions 57 which extend across and are attached to the

flanges 15 of said stiles. In these mountings are slidably mounted castings 58 which have cam surfaces 42, the same as the cam members 37 and engage the lugs 43 of the lever 27 to cooperate in latching the door in closed position. These castings are adapted to move along the wall 56 of the mounting 55 to adjust the same relative to the lugs 43. This is accomplished by means of two bolts 59 which extend through the angular portions 57 and 70 are threaded into the said castings. By turning the said bolts the said castings may be adjusted as required.

In Fig. 6 I have shown still another form of the invention in which the lever 27 instead of being constructed of bar material of rectangular cross-section is constructed of a round rod. When so constructed the lugs 43 may be dispensed with and the rod offset as indicated at 60 to form a member cooperating with the cam surfaces 42. With this form of the invention the ends 61 of the rod 60 may be threaded and attached to angle pieces 62 by means of nuts 63. These angle pieces are pivoted through rivets 64 to the ears 25 and serve to permit of swinging the lever 27 so as to cause the portion 60 to engage the cam surfaces 42 as with the other forms of the invention.

The invention is highly meritorious in that the device may be easily handled by the attendant and quickly and effectively inserted into closed position and effectively closed to seal the interior of the silo. The closing movement of the latching device with the invention is a downward movement such as is easily accomplished by the attendant while clinging to the rungs of the ladder. Upon removing the door from the frame the same may be held and handled through the same lever used for locking the closure in closing position. The entire device may be constructed of sheet metal and bar material of such shapes as are readily available in the market and can be constructed sufficiently light so as to reduce the cost without sacrificing as to the strength and rigidity of the structure at the same time being light and easy to handle. All of the steps being attached directly to the closure the labor involved in installing steps in conjunction with the silo are completely eliminated. Due to the fact that some of the steps are permanently fastened to the frame, the attendant has at all times a number of steps available for climbing the silo whether the doors are removed or in place. Adjustment of the latching device can be readily accomplished while the door is in closed position so as to secure the desired pressure upon the door proper necessary for effecting the degree of seal desired.

Changes in the specific form of my invention, as herein disclosed, may be made within the scope of what is claimed without departing from the spirit of my invention.

Having described my invention, what I claim as new and desire to protect by Letters Patent is:

1. A silo closure comprising a frame, a door adapted to seat against said frame, an ear formed on said door, a lever pivoted to said ear and extending outwardly from said frame to form a step, a cam member attached to said frame, cam engaging means formed on said lever and cooperating with said cam member for drawing the door inwardly against said frame upon the swinging of said lever into extended position, and a guard attached to said cam member cooperating with said cam engaging means for holding said lever from falling in the event of the detachment of the same from said ears.
2. A silo closure comprising a frame, a door adapted to seat against said frame, a lever pivoted to said door and extending outwardly from said frame to form a step, a cam member of Z-shaped cross-section having one of the legs thereof attached to said frame and the other of the legs thereof extending outwardly from said frame in offset relation thereto, said second leg being formed with a cam surface, a member on said lever adapted to engage said cam surface for drawing said door closed upon the swinging of said lever into outwardly extended position, said member extending past the cam surface and into the space formed through the offset in said cam member.
3. A silo closure comprising a frame, a door adapted to seat against said frame, a lever pivoted to said door and extending outwardly from said frame to form a step, a cam member of Z-shaped cross-section having one of the legs thereof attached to said frame and the other of the legs thereof extending outwardly from said frame in offset relation thereto, said second leg being formed with a cam surface, a member on said lever adapted to engage said cam surface for drawing said door closed upon the swinging of said lever into outwardly extended position, said last named member extending past the cam surface and into the space formed through the offset in said cam member, and means for moving one of said members relative to the other for regulating the pressure of said door upon said frame.
4. A silo closure comprising a frame, a door adapted to seat against said frame, a lever pivoted to said door and extending outwardly from said frame to form a step, a cam member of Z-shaped cross-section having one of the legs thereof attached to said frame and the other of the legs thereof extending outwardly from said frame in offset relation thereto, said second leg being formed with a cam surface, a member on said lever adapted to engage said cam surface for drawing said door closed upon the swinging of said lever into outwardly extended position, said base thereof resting upon one side of said door, a lever pivoted to the protruding end of the leg of said attaching member, and

member extending past the cam surface and into the space formed through the offset in said cam member, and a screw for moving one of said members relative to the other for regulating the pressure upon said door.

5. A silo closure comprising a frame, a door adapted to seat against said frame, a member formed on said door having an outwardly extending slot therein, a lever pivotally connected to said member having a pintle passing through said slot, a screw threaded in said member for engagement with said pintle for holding the same in adjusted position within said slot, and means cooperating with said lever for drawing said door in closed position, the adjustment of said pintle within said slot serving to vary the relation of said means to control the pressure of said door upon the frame.

6. A silo closure comprising a frame, a door adapted to seat against said frame, a pair of ears formed on said door intermediate the upper and lower ends thereof positioned adjacent the sides of said frame, said ears having outwardly extending slots formed therein, a U-shaped lever straddling said ears and being adapted to normally extend through the opening in said frame and outwardly therebeyond to form a step, pintles passing through the ends of said lever and through said slots for pivotally mounting said lever on said ears, screws threaded in said ears and adapted to engage said pintles for holding the same in adjusted position within said slots, cam members formed on said frame adjacent the side portions of said lever and means formed on said lever cooperating with said cam members to draw the door closed upon movement of said lever into extended position, said cam engaging means being adjustable relative to said cam members through the movement of said pintles within the respective slots in said ears.

7. A silo closure comprising a frame of U-shaped cross-section having a web and flanges, a door adapted to seat against one of the flanges of said frame, a U-shaped step pivoted to said door near its center and extending through the opening in said frame and along the web thereof and outwardly beyond the other of said flanges, said second flange being formed with apertures near its upper end in close proximity to the web and a second step extending through said apertures and attached to said web, said second step being angularly disposed relative to said first step.

8. A silo closure comprising a frame, a door adapted to seat against said frame and having a slot therethrough, a T-shaped attaching member having the outstanding leg thereof extending through said slot with the base thereof resting upon one side of said door, a lever pivoted to the protruding end of the leg of said attaching member, and

means cooperating therewith for drawing said door into engagement with said frame.

9. A silo closure comprising a frame, a door adapted to seat against said frame and disposed within the interior of the silo, said door having a slot extending therethrough, a T-shaped attaching member having the outstanding leg thereof extending through said slot and the base thereof positioned upon 10 the interior of the door, a lever pivoted to the protruding end of the leg of said attaching member and extending through said frame, and means on said frame for engagement with said lever to draw said door 15 against said frame.

10. A silo closure comprising a frame, a door adapted to seat against said frame, attaching means secured to said door, a lever pivoted to said attaching means, a member 20 on said lever, a second member on said frame cooperating with said other member, one of said members having a cam surface, means for guiding the member on said lever for movement toward and from said door to vary 25 the contacting position of said members, the member on said lever being immovable relative thereto during the operation of said lever.

11. A silo closure comprising a frame, a door adapted to seat against said frame, attaching means secured to said door, a lever pivoted to said attaching means, a member on said lever, a second member on said frame 30 cooperating with said lever, one of said members having a cam surface, means for guiding the end of said lever for movement toward and from the door to vary the position of 35 said members with respect to one another, the member on said lever being immovable 40 relative thereto during the operation of said lever.

12. A silo closure comprising a frame, a door adapted to seat against said frame, attaching means formed on said door, a lever pivoted to said attaching means, members 45 on said lever and frame cooperating with one another to draw said door closed, means for adjusting one of said members relative to the other to vary the pressure upon the door, the member on said lever being immovable 50 relative to said lever, and the member on said frame being immovable relative to said frame during the operation of said lever.

13. A silo closure comprising a frame, a door adapted to seat against said frame, attaching means formed on said door, a lever pivoted to said attaching means and extending outwardly from said door and past said frame, a member formed on said lever and 60 extending outwardly to one side thereof, a member formed on said frame and extending in the plane of movement of the member on said lever, and means for moving one of said members relative to the other to vary the 65 relative positions thereof.

14. A silo closure comprising a frame, a door adapted to seat against said frame, attaching means formed on said door, a lever pivoted to said attaching means, a cam member attached to said frame, means formed on 70 said lever and cooperating with said cam member for drawing the door against the frame upon the swinging of said lever, and a guard attached to said cam member cooperating with said cam engaging means on said lever for holding said lever from falling in the event of detachment from said attaching means, said guard being detached from said cam at one end to permit of the complete disengagement of said lever from said cam and 75 guard.

15. A silo closure comprising a frame, a door adapted to seat against said frame, attaching means formed on said door, a lever pivoted to said attaching means, a member 80 on said lever, means on said frame cooperating therewith for drawing said door against said frame upon the swinging of said lever, and a guard attached to said frame and cooperating with the member on said lever for holding said lever from movement relative to the frame in the event of detachment of the same from said attaching means.

16. A silo closure comprising a frame, a door adapted to seat against said frame, attaching means formed on said door, a lever pivoted to said attaching means, a plate-like member attached to said frame and having a portion thereof offset from the frame, a cam 95 formed along the edge of said offset portion, and means on said lever engaging said cam for drawing said door against said frame.

17. A silo closure comprising a frame, a door adapted to seat against said frame, attaching means formed on said door, a lever pivoted to said attaching means and adapted to be swung outwardly from said frame to form a step, members on said lever and frame co-operating with one another to draw said door closed when the lever is swung into extended position, a stop formed on the member mounted on said frame and adapted to engage the lever to hold the lever in extended position, and means for adjusting one of said members relative to the other to vary the pressure upon the door and to bring said lever into proper extended position to engage said stop when the proper pressure has been procured upon the door.

18. A silo closure comprising a frame, a door adapted to seat against said frame, attaching means formed on said door, a lever pivoted to said attaching means and adapted to be swung outwardly from said frame to form a step, a cam member attached to said frame, a cam engaging member formed on said lever and cooperating with said cam member for drawing the door inwardly against said frame upon the swinging of the lever into extended position, a stop formed on 120 125 130

said cam member for engaging said lever to hold the lever in extended position, and means for adjusting one of said members to vary the pressure upon the door and to bring 5 said lever against said stop when the lever is in proper extended position.

19. A silo closure comprising a frame, a door adapted to seat against said frame, attaching means formed on said door, a lever 10 pivoted to said attaching means and swingable in a plane substantially at right angles to the plane of said door, members on said lever and frame cooperating with one another to draw said door closed, and means for guiding 15 one of said members for movement in the plane of movement of said lever to vary the relative position of said members and the resultant pressure upon the door.

20. A silo closure comprising a frame, a door adapted to seat against said frame, attaching means formed on said door, a lever 20 pivoted to said attaching means and swingable in a plane substantially at right angles to the plane of said door, a cam member and 25 a cam engaging member, one thereof being on said lever and the other thereof being on said frame and cooperating with one another to draw said door closed upon the swinging of said lever, means for guiding 30 one of said members for movement in the plane of movement of said lever to vary the relative position of said cam member and cam engaging member and the resultant 35 pressure upon the door.

35. 21. A silo closure comprising a frame, a door adapted to seat against said frame, attaching means formed on said door, a lever, a fixed pivot for pivoting said lever to 40 said attaching means, a latching member on said lever adapted to cooperate with said frame for drawing said door into closing position, and means for varying the distance 45 between said latch means and pivot to vary the pressure upon said door.

45. 22. A silo closure comprising a frame, a door adapted to seat against said frame, a lever pivoted to said door and extending outwardly from said frame to form a step, a cam member attached to said frame, cam 50 engaging means formed on said lever and cooperating with said cam member for drawing the door inwardly against said frame upon the swinging of the lever into extended position, and a guard attached to said cam member cooperating with said cam engaging means for holding said lever from falling in the event of the detachment of 55 the same from said attaching means.

60. 23. A silo closure comprising a frame, a door adapted to seat against said frame, attaching means secured to said door, a lever pivoted to said attaching means, a member on said lever, a second member on said frame 65 cooperating with said other member, one of said members having a cam surface, means

for guiding the member on said frame for movement toward and from said door to vary the contacting position of said members, the member on said lever being immovable relative thereto during the operation of 70 said lever.

24. A silo closure comprising a frame, a door adapted to seat against said frame, a lever pivoted to said door, a member on said frame having a cam portion spaced from 75 said frame, a member on said lever adapted to engage said cam member for drawing the door closed, said member extending past the cam member and into the space between the cam member and frame.

80. 25. A silo closure comprising a frame, a door adapted to seat against said frame, a lever pivoted to said door, a guide secured to said frame, a member slidable along said guide, a member on said lever, one of said 85 members having a cam surface, said members cooperating to draw the door into closed position, and means for holding said member upon the frame in adjusted position relative to the frame.

90. 26. A silo closure comprising a frame, a door adapted to seat against said frame, a lever pivoted to said door, a guide secured to said frame, a member slidable along said guide, a member on said lever, one of said 95 members having a cam surface, said members cooperating to draw the door into closed position, and a screw for adjusting the position of said member on the frame along said guide to vary the pressure upon said door.

100. In testimony whereof I have affixed my signature to this specification.

EARL E. PRICE.
